Assistant Examiner — Clare Ann Gannon

(74) Attorney, Agent, or Firm — Kilpatrick Townsend & Stockton LLP

(57) **CLAIM**

The ornamental design for a shoe, as shown and described.

DESCRIPTION

FIG. 1 is a perspective view of a shoe, showing our new design; and,

FIG. 2 is a side view thereof.

The dashed lines show portions of the shoe that form no part of the claimed design. The solid lines show and surround portions of the shoe that form the claimed design.
